BURR REMOVER

Carl J. Honen, Youngstown, Ohio, assignor to The
McKay Machine Company, Youngstown, Ohio,
a corporation of Ohio

Application December 18, 1947, Serial No. 792,472

4 Claims. (Cl. 90—24)

1

This invention relates to the general art of manufacturing tubes in a continuous manner and more particularly to an improved apparatus for removing the exterior burr formed on the tubing during a butt-welding process of manufacture thereof. The apparatus of the invention is particularly applicable to tube mills of the continuous electric butt-weld type and the apparatus will be so described herein although it should be obvious as the description proceeds that the apparatus is useful in connection with any continuous tube mill wherein an exterior burr is thrown up, requiring removal in providing the finished product. A primary object of the invention is the provision of an improved exterior burr trimmer for tube mills which is capable of rapid and repeated movement from operating position to retracted position and vice versa without effecting adjustment of the apparatus which determines the depth of cut of the trimmer when in operative position. A further and more specific object of the invention is the provision in a continuous tube mill of the kind in which a continuous exterior burr is thrown up onto the tube of an improved arrangement for removing such thrown-up burr whereby the trimming tool is automatically retracted simultaneously with stoppage of the mill. This feature is highly advantageous in the operation of continuous tube mills since upon stoppage of the mill the metal of the burr begins to cool and to contract causing movement in the burr metal and in the cutting tool in a direction opposite to that which occurs during the cutting operation. Because the unsupported length of the cutting tool is deflected during the cutting operation due to the cutting pressure exerted, this reversal of pressure caused by the contracting burr causes the tip of the cutting tool to move through an arc, creating additional upward pressure as well as reverse pressure and as the tip is unsupported in this direction and has poor tensile qualities, it usually is fractured and must be removed for grinding or be replaced. Also, the cutting tool tip may be fractured by instantaneous reversal of the mill which commonly occurs upon emergency stopping thereof. Further, the severed flash or burr tends to weld onto the cutting tool and if the anchor point of the severed flash is pulled away from the tool in a reverse direction the tool is also likely to be fractured.

A still further object of the invention is the provision in a continuous butt-weld tube mill having an exterior burr trimming tool of an improved mounting for such tool whereby the tool will have greater rigidity with respect to the

2

tubing passing by it and whereby adjustment of the tool with respect to the passing burr to be removed will be facilitated.

The above and other objects and advantages of the invention will become apparent upon consideration of the following detailed specification and the accompanying drawing wherein there is disclosed a preferred embodiment of the invention.

10 In the drawing:

Figure 1 is a plan view of a tube mill of the continuous electric resistance butt-weld type utilizing the improved exterior burr trimming apparatus of the present invention;

15 Figure 2 is a side elevation of the mill of Figure 1;

Figure 3 is a side elevation, on an enlarged scale, of the burr trimming apparatus of the invention;

20 Figures 4 and 5 are views similar to Figure 3 but showing certain of the parts in section;

Figure 6 is a fragmentary view of a detail of the burr trimming assembly of the invention; and

25 Figure 7 is a further view of a mechanical detail of the invention, the view including a schematic showing of a control circuit which may be employed, in accordance with the invention, for automatically retracting the trimming tool upon stoppage of the mill motor.

30 Referring first to Figures 1 and 2 of the drawing, the reference numeral 10 indicates the main frame of an electric resistance continuous butt-weld tube mill having a pair of rotary electrodes 11 with a pair of backing rolls 12 and a pair of pressure rolls 13 positioned immediately outward of the welding throat of the assembly. The mill also comprises, in accordance with usual practice, a plurality of forming and feeding roll stands one of which is shown at 14 and as indicated in Figure 1 of the drawing these various forming and feeding roll stands are driven by a common shaft 15 which in turn is driven by an electric motor 16 through the multiple V belt drive 17. For illustration purposes, motor 16 is shown as being energized through a line comprised of the conductors L1 and L2. As is well understood in the art the rotary electrodes 11 as well as the backing rolls 12 and the pressure rolls 13 are all supported for free rotation so that the tubing is advanced through the mill solely by the forming roll stands one of which is shown at 14. It will

35 be further understood that in the assembly shown the formed but open cleft tubing issuing from the stand 14 will be butt welded by the electric resistance method in the welding throat provided by the electrodes 11 and rolls 12 and the fresh

soft weld will be held together by the pressure rolls 13 acting in conjunction with the welding throat until the weld metal has cooled to adequate strength. In this process a burr is thrown up both on the interior and exterior of the tubing. To remove the exterior burr I provide the apparatus now to be described.

The exterior burr trimming assembly of my invention may conveniently be supported on the housings 16 of a straightening roll stand and, as shown, such housings may be formed with inclined surfaces 17. Securely fastened to the surfaces 17 in spanning relation to the two housings 16 of the straightening roll stand is a keystone-shaped bar 18 on which is slideably mounted a block 19. To slideably move the block 19 along the bar 18 and to secure the same in adjusted position I may provide a screw 20 which is rotatably secured relative to the bar 18 but which has screw threaded connection with the block 19 whereby the latter will be moved in one lateral direction or the other upon rotation of the screw 20.

Slideably mounted in suitable upwardly extending ways formed on the block 19 is a carrier 21 having at its upper end an integral yoke 22 for engaging opposite sides of an eccentric 23. The eccentric 23 is keyed onto a shaft 24 which is journaled in brackets 25 extending upwardly from and rigidly secured to opposite ends of the bar 18. Shaft 24 has keyed to one of its ends a pinion 25 meshing with a rack 26 coupled with the piston rod of a double-acting hydraulic cylinder 27. The gear ratio of parts 25, 26 and the length of stroke of the cylinder 27 is such as to cause approximately 180° rotation of the eccentric 23 upon actuation of the cylinder whereby the block 19 may be moved from lowermost to uppermost position upon such actuation.

Slideably mounted in a suitable upwardly extending way formed in the block 21 is the shank 28 of a tool holder 29 and screw-threadedly received in a longitudinal threaded bore formed in the top of the shank 28 is a headed screw 30. The shank of screw 30 is rotatably received in a bore formed in a lug 31 which is integral with the carrier 21 and engaging opposite sides of the lug 31 is the head of the screw 30 and a collar 32 which is rigidly secured to the shank of the screw 30. In this manner the screw 30 is held against axial movement relative to the lug 31 so that upon rotation thereof the tool holder 29 may be adjusted up or down and retained in adjusted position. Removably held in the holder 29 is one or more cutting tools 33 which in accordance with usual practice are contoured complementary to the curvature of the particular tubing being made so that upon removal of the outward flash or burr the finished tubing will be perfectly round in exterior outline.

In accordance with the present invention the scarfing tools 33 are automatically raised away from the tubing upon stoppage of the mill and, further, will not be again lowered onto the tubing until the cold and hardened burr has passed the trimmer. The release of the tool from retracted position may be accomplished either manually or automatically in response to the passage of sufficient tubing but for simplicity the manual release is incorporated in the present specifically described embodiment. Referring again to Figure 1 it will be observed that the main mill motor 16 is energized from a suitable source by the conductors L1 and L2 in which energizing circuit there is positioned a control switch 34 and a load

relay 35. Cylinder 27 is supplied at opposite ends with hydraulic fluid pressure under the control of a four-way valve 36 which when actuated by energization of a solenoid 37 is operative to admit fluid to the cylinder 27 in such direction as to cause the tool 33 to be retracted. When solenoid 37 is deenergized a biasing spring 38 reverses valve 36 and fluid is admitted to the opposite end of cylinder 27 to move the tool 33 down into engagement with the work (tubing).

Solenoid 37 is arranged to be energized from a suitable source through the closure of a contactor 39 on a relay 40 having an operating coil 41. Coil 41 is, in turn, arranged to be energized from a suitable source through the normally closed contactor 42 of the load relay 35 and in parallel with the contactor 42 is a normally open contactor 43 of the relay 40 to provide a holding circuit the function of which will be presently described. In this holding circuit is a normally closed manual switch 44.

With the control elements relatively positioned as shown in Figure 1 the mill motor 16 is energized to deliver tubing and the deenergization of solenoid 37 indicates that the burr removing tool 33 is in contact with the moving work. If now for any reason the production is to be interrupted as, for example, by stoppage of motor 16 through opening of switch 34 the relay 35 will drop out closing contactor 42 thereby energizing relay 40 which in turn through contactor 39 energizes solenoid 37 to raise the tool 33 away from the work. The contactor 43 and normally closed switch 44 provides a holding circuit for the energization of coil 41 so that even after operation of the mill is resumed and contactor 42 is again raised the solenoid 37 will remain energized to hold the tool 33 in retracted position. Thus, in the event welded tubing has been allowed to remain in the mill during the stoppage the continued retraction of the tool 33 after resumption of operation will allow time for the hardened burr to pass under the scarfing tool 33 or, alternatively, if a new length of tubing is being run the continued retraction of the tool will prevent the leading end of the length from engaging the tool and breaking it off. When the tool release is arranged for manual actuation the operator momentarily opens the switch 44 when proper additions are encountered and immediately the solenoids 41 and 37 are deenergized to allow the tool to come down into proper adjusted engagement with the work.

It should now be apparent that I have provided an improved exterior burr trimming system for a continuous butt-weld tube mill which accomplishes the objects initially set out. The apparatus is simple in design, economical to construct, and may readily be carried in a rugged and durable manner on any properly located existing frame structure of the welding mill assembly. The apparatus is such that the scarfing tool may readily be adjusted either tangentially or radially of the tube and the apparatus will retain its tool adjustment even though the tool is subjected to repeated retracted movements. Further, the apparatus provides for the automatic retraction of the tool upon interruption of the operation of the tube forming and welding mill and also for the retention of the tool in retracted position until conditions are proper for its release. This latter feature contributes quite materially to the ease and precision of control over the tube mill as a whole.

The above specifically described embodiment of

the invention should be considered as illustrative only as obviously many changes may be made therein without departing from the spirit or scope of the invention. Reference should therefore be had to the appended claims in determining the scope of the invention.

What I claim is:

1. In a continuous butt-weld tube mill having a mill operating motor to advance the tubing through and out of the mill and a scarfing tool to remove the exterior burr thrown up on the tubing in the welding process the combination of power means to move said tool to retracted position away from the outer periphery of the tubing issuing from the mill, means automatically responsive to deenergization of said motor to actuate said power means, holding means to maintain actuation of said power means upon resumption of energization of said motor, and manually releasable means for said holding means.

2. Exterior burr removing apparatus for continuous butt-weld tube mills comprising in combination a bar adapted to be supported transversely of and above the path of travel of tubing issuing from the mill, a block slideable along said bar and means to retain said block in adjusted position on said bar, a carrier slideably mounted on said block for up and down movement relative thereto, power means carried on said bar for moving said carrier between predetermined upper and lower positions, a tool slide mounted on said carrier for vertical sliding movement thereon, means to retain said slide in adjusted position on said carrier, and a burr removing tool carried by said slide.

3. Exterior burr removing apparatus for continuous butt-weld tube mills comprising in com-

bination a bar adapted to be supported transversely of and above the path of travel of tubing issuing from the mill, a block slideable along said bar and means to retain said block in adjusted position on said bar, a carrier slideably mounted on said block for up and down movement relative thereto, said carrier having a yoke at its upper end, a shaft journaled on said bar and having substantially parallel relation therewith, an eccentric on said shaft positioned within said yoke whereby rotation of said shaft causes said carrier to move vertically, a cylinder, a rack and pinion interconnecting the rod of said cylinder with said shaft, a tool slideable on said carrier adapted to have vertical movement relative thereto, means to secure said slide in adjusted position on said carrier, and a burr removing tool on said tool slide.

4. Apparatus according to claim 3 further including means to control the flow of fluid to said cylinder, and means operable automatically in response to the interruption of movement of tubing past said tool to admit fluid pressure to said cylinder thereby retracting said tool away from said tubing.
